(57) CLAIM

The ornamental design for a “brush”, as shown and described.

DESCRIPTION

FIG. 1 is a front perspective view showing one embodiment of a “brush” incorporating the design of my invention;

FIG. 2 is a top view thereof;

FIG. 3 is a bottom view thereof;

FIG. 4 is a side view thereof;

FIG. 5 is another side view thereof;

FIG. 6 is a front view thereof;

FIG. 7 is a rear view thereof;

FIG. 8 is a front perspective view showing another embodiment of a “brush” incorporating the design of my invention;

FIG. 9 is a top view of the brush shown in FIG. 8;

FIG. 10 is a bottom view of the brush shown in FIG. 8;

FIG. 11 is a side view of the brush shown in FIG. 8;

FIG. 12 is another side view of the brush shown in FIG. 8;

FIG. 13 is a front view of the brush shown in FIG. 8; and,

FIG. 14 is a rear view of the brush shown in FIG. 8.

The part of the dotted area shown on the handle portion of the brush in FIGS. 8 to 14 illustrates that the area has a different surface pattern or color, and/or made of a different material.
